UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

LOCK.

1,229,335.

Specification of Letters Patent. Patented June 12, 1917.

Application filed February 12, 1914. Serial No. 818,399.

To all whom it may concern:

Be it known that I, JOHN H. SHAW, a citizen of the United States, residing in the city and county of New Haven and State 5 of Connecticut, have invented certain new and useful Improvements in Locks, of which the following is a full, clear, and exact description.

This invention relates to locks, and more 10 particularly to that type of lock in which a latch bolt is adapted to be retracted from the outside of the door by a knob, and by suitable key mechanism, and from the inside of the door by a knob, there being suitable stop work or night latch mechanism 15 associated with the outside knob, whereby it may be prevented from turning. My improvements are herein shown and described as applied to a union or escutcheon lock, but 20 it will be manifest from the following description that the invention is applicable to locks of other kinds.

The primary object of the invention is to provide improved means for controlling the 25 operation of the stop work or night latch mechanism, which is usually accessible at the face or front of the lock. It is intended to furnish a lock wherein it is impossible to throw off the stop work or night latch 30 mechanism, by means of an instrument inserted between the lock front and the strike plate, and in which the stop work may only be thrown off, or rendered inoperative, by a person familiar with my improved construction. More particularly, it is aimed to 35 provide means to permit the throwing off of the stop work only when the inside knob is actuated in a particular manner. Furthermore, it is aimed to provide a lock wherein 40 the stop work or night latch mechanism, which coöperates in the usual way with the outside hub of the latch retracting mechanism, is directly controlled by another hub of the latch retracting mechanism. An- 45 other important feature resides in the construction by which the last named hub, after having been turned from its normal position to release the stop work, and after the release of the outside hub, can return to 50 its normal position without displacing the member for dogging the outside hub.

To these and other ends, the invention consists in the novel features and combinations of parts to be hereinafter described 55 and claimed.

In the accompanying drawings,

Figure 1 is an inside view of the outer escutcheon of a union lock embodying my improvements, with the back plate removed, and showing the latch bolt in its protracted 60 position.

Fig. 2 is a similar view, showing the latch bolt retracted by operation of the inside hub.

Fig. 3 is a section of the complete lock, 65 partly on line 3—3 of Fig. 1, and partly on line 3^a—3^a, with some parts in elevation.

Fig. 4 is a section of line 4—4 of Fig. 1.

Fig. 4^a is a section on line 4^a—4^a of Fig. 4.

Fig. 5 is a view similar to Fig. 1, with the 70 latch bolt and yoke omitted, showing the stop work in its dogging position relative to the outer hub.

Fig. 6 is a reverse view of Fig. 5.

Fig. 7 is a view similar to Fig. 5, but 75 showing the inside hub turned to release the stop work, and showing the stop work in its inoperative or "off" position.

Figs. 8 and 9 are details of the dogging 80 slide of the stop work; and

Figs. 10 and 11 are detail views of the releasing slide of the stop work.

Referring to the drawings, I have shown my improvements applied to a union lock having an outside escutcheon 20, a face 85 plate 21, a pivoted latch bolt 22 projecting through the face plate, and a yoke 23 for retracting the latch bolt. The yoke 23 is adapted to be actuated by any of three hubs or rollbacks 24, 25 and 26. The hub 26 is 90 suitably connected to the shank or spindle 27 of an outside knob 28. The middle hub or rollback 25 is attached to a rod 29 forming part of a pin tumbler lock mechanism 30, housed in the knob 28, and adapted to 95 be operated by a suitable key 31. The rollback 24 is connected with the shank or spindle 32 of an inside knob 33, connected with the inside escutcheon 34 of the lock, as shown in Fig. 3.

The outside hub 26 is adapted to be dogged by a dogging slide 35 having a button or plunger head 36, accessible at the face plate of the lock. The slide 35 in the form shown has an upright arm 37, provided with a notch 38, adapted to take over a lug 39 on the outside hub 26, and thereby fix said hub against movement. The slide or stop member 35 forms part of a night latch mechanism associated with the outer 110

hub, the other parts of which mechanism are constituted by a releasing slide 40, having a button or plunger head 41, accessible at the face of the case, and by a walking beam 42, pivoted in the case at 43, and connecting the slides 35 and 40 for movement in opposite directions. The walking beam 42 is pivoted to the slide 35 by a pin 44, and it is pivoted to the slide 40 by a pin 45. By 10 this arrangement of the slides and walking beam, the pushing in of one slide will result in the outward movement of the other, as usual in this class of devices.

In the lock illustrated, the releasing slide 15 40 of the night latch mechanism coöperates in a novel manner with the inside hub 24, whereby the position assumed by said hub controls the operation of the night latch mechanism from the face of the lock. To 20 this end, the releasing slide 40 is provided with an extension 46, having an upstanding lug 47, arranged in front and about centrally of the inside hub 24, as shown in Fig. 5. The inside hub, on the other hand, 25 has a forwardly projecting nose or lug 48 which, in the normal position of the hub, lies back of the lug 47, in such close proximity thereto as to prevent the slide 40 from being pushed inward. Hence, when the in 30 side hub is in its normal position and the slide 35 of the stop work is in dogging position relative to the outside hub 26, the releasing slide 40 will be blocked by the lug or nose 48 against such a complete actuation 35 as is necessary to release the dogging slide. When, however, the inside hub is partially turned by the inside knob 33, as shown in Fig. 7, the lug or nose 48 will be moved out of the path of the lug 47 on the releasing 40 slide to such an extent as to permit a complete movement of said slide to release the outside hub, as shown in Fig. 7. The intermediate hub or rollback 25 not being provided with a blocking device for the releasing 45 slide has no coöperation with the stop work, and hence the control of the stop work is confined to the inside knob. However in the broad aspects of the invention, I do not limit myself to a construction in which a 50 hub controlling the operation of the stop work in a direct manner, is operated by the inside knob, as distinguished from some other operating instrumentality. In the construction shown, the movement of the 55 inside hub 24 into non-blocking position relative to the releasing member of the stop work is only a slight movement which does not necessitate a complete retraction of the latch. The stop work may therefore be released for manual manipulation in a very 60 easy manner by one conversant with the lock construction. Moreover, the embodiment herein shown and described is so constructed 65 that after the hub has been turned out of its normal position to permit the release

of the dogging member for the outside hub, the inside hub may return readily to its normal position. To this end, the connection of the releasing slide 40 with the walking beam 42 is a so-called "one-way" connection, constituted by a notch 45^a in the walking beam, taking over the pin 45 on the slide, and permitting an outward movement of the slide without a corresponding movement of the walking beam. Hence, when 70 the hub 24 has been turned to non-blocking position relatively to the stop work, and the dogging slide has been released, as shown in full lines in Fig. 7, the hub 24 may swing back to its normal position under the 75 influence of the spring controlled yoke 23, in doing which it pushes the releasing slide outward without affecting the position of the walking beam and the dogging member of the stop work. In other words, the releasing slide 40, being free for individual movement in an outward direction, does not prevent the hub from moving back to its 80 normal position, as shown by the dotted lines in Fig. 7, after the dogging slide has 85 been thrown off by an inward movement of the releasing slide. 90

When the dogging member of the stop work has been moved into its inoperative position, as shown in Fig. 7, it may be 95 readily reengaged with the outside hub merely by pushing said dogging member inward. In this operation the walking beam 42 will be swung on its pivot into a position in which the notch 45^a engages the pin 45 of the releasing slide, as shown in Fig. 6. When in its "off" position the stop work mechanism can always be actuated manually to dog the outer latch retracting device, but it can only be actuated to release such outer 100 retracting device when a rotary member, such as a hub, normally blocking the movement of the releasing member of the stop work, is turned out of its blocking position. 105

Various modifications in the construction 110 may be adopted within the scope of the invention as defined in the claims.

What I claim is:

1. In a lock, a latch bolt, inner and outer manual retracting devices therefor, manually movable stop work for the outer retracting device, key mechanism for retracting the latch bolt, and means for normally preventing a releasing movement of said stop work, and for preventing such releasing movement when the key mechanism is operated, said preventing means being movable into an inoperative position when said inner manual retracting device is operated; substantially as described. 115

2. In a lock, a latch bolt, inner and outer knobs for retracting the same, manually movable stop work associated with the outer knob, key mechanism for retracting the latch bolt, and means releasable by the inner 120 125 130

knob only for blocking the movement of the stop work from operative into inoperative position; substantially as described.

3. In a lock, a latch bolt, inner and outer manual retracting devices therefor, manually operable stop work accessible at the face of the lock for dogging the outer retracting device, key mechanism for retracting the latch bolt, means to lock said stop work against a releasing movement, and means operated by the inner retracting device, but unaffected by said key mechanism, to shift the locking mechanism for the stop work to an inoperative position; substantially as described.

4. In a lock, a latch bolt, inner and outer manual retracting devices therefor, manually operable stop work associated with the outer retracting device, and including a dogging member and a releasing member, key mechanism for retracting the latch bolt, means to lock the releasing member of said stop work against movement in one direction, and means operated by the inner manual retracting device, but unaffected by said key mechanism, for releasing said locking means; substantially as described.

5. In a lock, a latch bolt, inner and outer retracting hubs therefor, manually operable stop work to dog and release the outer hub, key mechanism for retracting the latch bolt, and means to prevent a releasing movement of said stop work except when said inner hub is operated; substantially as described.

6. In a lock, a latch bolt, a hub for retracting the same from the outside of the door, manually operable means to dog said hub, key mechanism for retracting the latch bolt, a rotary member to control the releasing movement of said dogging means independently of said key mechanism, and means to operate said rotary member; substantially as described.

45 7. In a lock, a latch bolt, an outer manual retracting device therefor, manually operable stop work, including a member to dog said outer retracting device, and a releasing member, a rotary hub having a part normally projecting into the path of said releasing member, and manually operable means to turn said hub out of its blocking position; substantially as described.

8. In a lock, a latch bolt, an outer manual retracting device therefor, manually operable stop work associated with said outer retracting device, and including a dogging member and a releasing member, and a retracting member for said latch bolt which 60 stands in the path of said releasing member when the latch bolt is fully protracted; substantially as described.

9. In a lock, a latch bolt, a hub for retracting the same from the outside of the door, manually operable stop work, includ-

ing a dogging member for said hub, and a releasing member for said dogging member, and a second hub for retracting said latch bolt coöperating directly with said releasing member to prevent a releasing movement thereof; substantially as described.

10. In a lock, a latch bolt, a hub for retracting the same from the outside of the door, manually operable stop work, including a slide for dogging said hub and a releasing slide, and a second hub for retracting the latch bolt so positioned relatively to said releasing slide as to normally prevent a releasing movement thereof; substantially as described.

11. In a lock, a latch bolt, a hub for retracting the same from the outside of the door, manually operable stop work, including a dogging slide for said hub and a releasing slide, a second hub to retract the latch bolt, and coöperating projections on said releasing slide and said second hub respectively for preventing a releasing movement of the stop work when said second hub is in its normal position; substantially as described.

12. In a lock, a latch bolt, hubs for retracting the same, night latch mechanism for dogging one of said hubs, having a releasing member coöperating directly with another hub, said releasing member being normally blocked against releasing movement by said second named hub, and being free for releasing movement only when said hub is turned to a predetermined extent; substantially as described.

13. In a lock, a latch bolt, hubs for retracting the same, night latch mechanism for dogging one of said hubs, having a releasing member coöperating directly with another hub, said releasing member being normally blocked against releasing movement by said second named hub, and being free for releasing movement only when said hub is turned to a predetermined extent, said releasing member being freely movable in the opposite direction independently of the other parts of the night latch mechanism; substantially as described.

14. In a lock, a latch bolt, hubs for retracting the same, a dogging slide for one of said hubs, a releasing slide for said dogging slide, normally blocked against inward movement by another hub, but free for inward movement when said hub has been turned, and means to permit an independent outward movement of said releasing slide after it has been pushed inward; substantially as described.

15. In a lock, a latch bolt, hubs for retracting the same, a dogging slide coöperating with the outside hub, a releasing slide for said dogging slide normally blocked by another of said hubs, and a walking beam

- connecting said slides and having a one-way connection with one of them; substantially as described.
16. In a lock, a latch bolt, hubs for reTRACTING the same, night latch mechanism for dogging one of said hubs having a releasing member coöperating with another hub, said releasing member being normally blocked against releasing movement by said 10 second named hub but free for releasing movement when said hub has been turned from its normal position, and means to permit a return of said hub to its normal position without changing the position of said 15 dogging member; substantially as described.
17. In a lock, a latch bolt, an outer manual reTRACTING device for said bolt, a member to dog said reTRACTING device, a releasing member for said dogging member, a rotary member 20 normally blocking a releasing movement of said releasing member, but permitting a releasing movement thereof when said rotary member has been turned, and means for permitting a return movement of 25 said rotary member to its normal position without changing the position of said dogging member; substantially as described.
18. In a lock, a latch bolt, reTRACTING hubs therefor, and night latch mechanism to dog

one of said hubs, including a releasing member having means whereby it is dogged by another of said hubs against releasing movement; substantially as described.

19. In a lock, a latch bolt, an outer manual reTRACTING device for said latch bolt, stop work for said manual reTRACTING device including a dogging slide and a releasing slide, and latch reTRACTING mechanism separate from the latch bolt proper, operable from the inside of the door and constructed and arranged to control the operation of said stop work; substantially as described.

20. In a lock, a latch bolt, a reTRACTING hub therefor at the outside of the door, a reTRACTING hub at the inside of the door, stop work for the outside hub including a dogging slide and a releasing slide, a yoke for reTRACTING the bolt by means of said hubs, and means independent of the latch bolt and operated by the movement of the inside hub for controlling the operation of said stop work; substantially as described.

In witness whereof, I have hereunto set my hand on the 2nd day of February, 1914.

JOHN H. SHAW.
